(57) **CLAIM**

The ornamental design for a clip for writing instrument, as shown and described.

DESCRIPTION

FIG. 1 is a top front left perspective view of a clip for a writing instrument according to a first embodiment of my new design;

FIG. 2 is a bottom rear right perspective view of the clip shown in FIG. 1;

FIG. 3 is a front view of the clip shown in FIG. 1, wherein the rear view is a mirror image of the front view;

FIG. 4 is a left side view of the clip shown in FIG. 1;

FIG. 5 is a right side view of the clip shown in FIG. 1;

FIG. 6 is a plan view of the clip shown in FIG. 1;

FIG. 7 is a bottom view of the clip shown in FIG. 1;

FIG. 8 is a cross-sectional view of the clip shown in FIG. 1, as indicated in FIG. 6;

FIG. 9 is a top front left perspective view of a clip shown in FIG. 1, wherein the clip is attached to a writing instrument;

FIG. 10 is a left side view of the clip shown in FIG. 1, wherein the clip is being used to remove a nib of a writing instrument;

FIG. 11 is a top front left perspective view of a clip for a writing instrument according to a second embodiment of my new design;

FIG. 12 is a bottom rear right perspective view of the clip shown in FIG. 11;

FIG. 13 is a front view of the clip shown in FIG. 11, wherein the rear view is a mirror image of the front view;

FIG. 14 is a left side view of the clip shown in FIG. 11;

FIG. 15 is a right side view of the clip shown in FIG. 11;

FIG. 16 is a plan view of the clip shown in FIG. 11;

FIG. 17 is a bottom view of the clip shown in FIG. 11;

FIG. 18 is a cross-sectional view of the clip shown in FIG. 11, as indicated in FIG. 16;

FIG. 19 is a top front left perspective view of a clip shown in FIG. 11, wherein the clip is attached to a writing instrument; and,

FIG. 20 is a left side view of the clip shown in FIG. 11, wherein the clip is being used to remove a nib of a writing instrument.

The dashed broken lines in the drawings show portions of the clip for a writing instrument that form no part of the claimed design. The dash dot broken lines define the bounds of the claimed design and form no part thereof.
